UNITED STATES PATENT OFFICE

ERIK AUGUST DEHMER, OF STOCKHOLM, SWEDEN, ASSIGNOR TO CAPULATOR-AKTIE-BOLAGET, OF STOCKHOLM, SWEDEN, A CORPORATION OF SWEDEN

SCREW PROPELLER

Application filed July 24, 1929, Serial No. 380,633, and in Sweden and Germany August 1, 1928.

This invention relates to the construction of a screw propeller having for its purpose to increase the useful effect by reduction of the losses emanating from the usual churning of the water.

5 The invention is illustrated in the accompanying drawing in which:—

Fig. 1 shows the propeller seen from astern.

Fig. 2 is a diagrammatical projection of one 10 of the propeller blades on a spherical surface coinciding with the pressure surface of the blade, and

Fig. 3 shows the blade stretched flat.

The direction of rotation of the propeller 15 is shown by arrows in the drawing (Figs. 1 and 2) and the blades having a curvature known in itself are at the leading edge provided with a cutting cam *a* or the like.

The pressure surface of the blades coincides in a known manner with an element of a sphere, and thus it is concave as well in longitudinal as in transversal direction, as diagrammatically shown in Fig. 2.

If the root of the propeller blade is supposed to stand on one of the great circles *b*' 20 of the sphere, so that a straight line *b* between the end points of the root lies in the plane of that great circle, then a line *x* from the middle of the line *b* to the tip of the blade, i. e. the end 25 point having the greatest radius, counted in the direction of rotation will form a forward angle to a diametrical plane *y* through the middle of said line *b* in the sphere coinciding with the pressure surface of the blade, the 30 centre of such sphere being designated *O* (Fig. 2). Further, if the pressure surface of the blade is assumed to be cut by planes *c*', *d*' . . . &c. parallel to the plane of the great circle, then the bases *c*, *d* . . . &c. of the segments of the arcs of the blade surface so cut 35 are at angles to the base *b* of the root segment and to each other, these angles being greater the farther the section planes are from the plane of the great circle.

40 The root base *b* in the direction of rotation forms an obtuse angle with the propeller shaft, the axis of which is assumed to be positioned in the plane *w* (Fig. 2), and the bases *c*, *d* . . . &c. form corresponding angles with 45 the plane *w*, these angles being smaller the

farther such bases are from the blade root or from the base *b*. The element of the great circle plane bisected by the plane *w* and the cam *a* at the leading edge of the blade are located at opposite sides of the diametrical 55 plane *y* through the middle of the blade root.

What I claim and desire to secure by Letters Patent is:—

Improvement in screw propellers having blades of common contour provided at the 60 leading edge with a cutting cam and a pressure surface coinciding with an element of a sphere, such pressure surface being shaped in such a manner; that a base line of a cross section at the blade root coinciding with the 65 great circle plane of the sphere forms an angle to the base lines of cross sections taken at a distance from and parallel with the great circle plane, such angle being greater the farther the section planes are from the plane 70 of the great circle; and that a plane through the axis of the propeller shaft and the middle of the blade root base line counted in the direction of rotation of the blade forms obtuse 75 angles to said blade root base and to the base lines of the sections taken at a distance from and parallel with the great circle plane such angles being smaller the farther said base lines are from the blade root base.

In testimony whereof I have signed my 80 name to this specification.

ERIK AUGUST DEHMER.
